BOBBIN RELEASE FOR WEFT REPLENISHING LOOMS

Walter H. Wakefield, Worcester, Mass., assignor to Crompton & Knowles Loom Works, Worcester, Mass., a corporation of Massachusetts

Application June 1, 1936, Serial No. 82,830

12 Claims. (Cl. 139—232)

This invention relates to improvements in weft replenishing looms more particularly of the multicolor type and it is the general object of the invention to provide improved means for releasing an untransferred bobbin.

In the type of multicolor weft replenishing loom commonly used in this country the reserve bobbins of differing colors are arranged in adjacent vertical stacks and at the time of transfer a bobbin is drawn from the stack corresponding to the exhausted shuttle and moves to a common transfer position. Transferring means later push the reserve bobbin into the shuttle against the action of yielding supports which hold the bobbin temporarily over the shuttle. If for any reason the shuttle should not be properly boxed on the transferring beat, a shuttle feeler revokes the transfer, in which case the reserve bobbin is left on the yielding supports in transfer position. Inasmuch as looms of this type operate with a series of weaving shuttles any one of which may become active it is necessary to rid the magazine of the untransferred bobbin so that if the next transfer called for is a different color there will be no confusion in pattern effects.

In order to accomplish this general result it has been customary heretofore to move the rear bobbin supports backwardly to provide an open throat in the magazine large enough to pass the bobbin. With such a release, however, the forward supports remain at rest and the bobbin moves down their inclined supporting surfaces in a direction having a rearward component toward the lay. This rearward discharge occasionally results in breakage due to the fact that the reserve bobbin is caught either in front of or on some part carried by the lay and forced against a part of the magazine.

It is an important object of my present invention to reverse the method heretofore employed and move the forward supports forwardly so that as the bobbin rolls down the rear supports it will have a direction of motion with a forward component away from the lay, resulting in a lessened likelihood that the falling bobbin will become entangled with the lay.

Looms of the type specified are now constructed with a front bobbin butt support which yields against a relatively heavy spring pressure and a forward tip support yielding against light pressure. It is a further object of my present invention to connect these two supports together in such a way that movement of the butt support will cause movement of the tip support.

It is a further object of my invention to con-

nect the front butt support with a shuttle feeler and cause the latter when being reset after either a normal or revoked transfer to move the support to bobbin releasing position. I do not wish to be limited, however, to the use of a shuttle feeler to effect releasing movement of the bobbin butt support.

Heretofore, the transfer latch and shuttle feeler have been held yieldingly in transfer position by a spring lock operated by a top rocking shaft 10 on the magazine. It is a further object of my invention to use the heavy spring for the bobbin butt support to hold the shuttle feeler and transfer latch yieldingly in position, the spring operating to move the feeler, latch and support to transfer position. A connection between the support and shuttle feeler cooperates with the spring to form a yielding toggle lock acting similarly to the previously used lock which is not now necessary.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is an end elevation of a multicolor weft replenishing mechanism having my invention applied thereto as viewed from the center of the loom, the magazine being set for transfer,

Fig. 2 is a horizontal section on line 2—2, of Fig. 1,

Fig. 3 is a front elevation of the lower part of the magazine, taken in the direction of arrow 3.

Fig. 4 is a view similar to the lower portion of Fig. 1 but with the shuttle feeler and bobbin supports reset in normal position.

Fig. 5 is a detailed end elevation of the lower part of the outside or tip end of the magazine, and taken in the direction of arrow 5, Fig. 3,

Fig. 6 is a detailed front elevation of an upper part of the magazine taken in the direction of arrow 6, Fig. 1.

Referring to the drawings, I have shown a loom frame 10 supporting a magazine M having pivoted thereon a transfer lever 11 which supports a latch holder 12. A latch 13 in the holder is adapted for engagement with a bunter 14 on the lay L on transferring beats of the loom.

The magazine includes in its construction a vertically reciprocating block 15 to which is pivoted an actuator lever 16 one end of which is attached pivotally to a vertical rod 17. The latter has operative engagement with a color slide 18 to give the latter rocking motions in op-

posite directions. Vertical bobbin releasing slides 19, 20, 21 and 22 are provided, respectively, for the weaving shuttles of the loom. In the present instance it is assumed that the loom operates with four different shuttles which are operative one at a time in a succession determined by the pattern mechanism not shown. The slide 18 may be positioned longitudinally by a lever 23 controlled by the box motion so that one or another of the slides 19, 20, 21 or 22 will be placed for lifting by the color slide 18 when the detector mechanism not shown indicates exhaustion of weft in the active shuttle.

The rock shaft 30 in the upper part of the magazine is adapted for slight rocking motion whenever a previously elevated vertical slide is depressed by the color slide. When the shaft 30 is rocked preparatory to a transferring operation, a shuttle feeler 31 is dropped from its normal elevated position shown in Fig. 4 to the transferring and shuttle feeling position shown in Fig. 1. The shuttle feeler is mounted on a carrier 32 pivoted as at 33 to the magazine frame and to a rod 34 at 35. The upper end of rod 34 is connected to arm 36 secured to the shaft 30. The forward end of rocker shaft 30, right hand end in Fig. 1, has secured thereto an arm 37 carrying a block 38 to move in a slot 39 formed in an arm 40 of a rocking lever 41. The latter is pivoted as at 42 to the magazine frame and is attached to a depending rod 43 the lower end 44 of which extends under the latch 13. A stop screw 45 in the arm 40 is positioned for engagement with a part 46 of the magazine frame to limit motion of shaft 30. The magazine is essentially the same as that set forth in prior patent to Ryon No. 1,030,748, to which reference may be had for further description. It is considered sufficient for the present description to state that normally the latch 13 is down and the shuttle feeler 31 up, and that they move to the other extremes of their motion, as in Fig. 1, when the magazine is set for transfer.

In order that a reserve bobbin B may be held in transfer position there are usually provided four supports all of which at the present time are made yielding. The rear butt support 50 is suspended on a link 51 pivoted at 52 to the magazine frame and extends rearwardly and upwardly to have engagement with an arm 53 pivoted to the magazine frame. The support 50 has a downwardly and forwardly extending bobbin guiding surface 55 which may be rounded somewhat as indicated in Fig. 1. This surface will ordinarily bear the relation to the bobbin B awaiting transfer as set forth in Fig. 1, the lower part of the surface 55 extending forwardly and under the rear part of the butt of the bobbin. A spring 57 connected to the support 50 renders the latter yielding and during normal transfer said support moves to the left as viewed in Fig. 1 as the butt of the bobbin is pushed down into the shuttle S by the transfer arm 11. For further details as to the construction and operation of the support 50 reference may be had to Ryon Patent No. 1,366,950.

The front of the bobbin butt is held by a second support 60 having a bobbin guiding surface 61 which extends downwardly and rearwardly, terminating in a substantially vertical portion 62. A bridge 63 connects the support 60 with an arm 64 pivoted to the magazine frame at 65, and a spring 66 acts to turn the support 60 in a right hand direction around pivot 65. The bridge engages the bottom of the magazine frame to act as a stop and limit motion of the support under

action of the spring. At the time of transfer the spring 66, which is stronger than spring 57, will hold the surface 61 relatively immovable with respect to the magazine so that rear support 50 yields in order to permit the bobbin butt to move into the shuttle. Support 60 may be substantially the same as shown in Patent No. 1,652,604.

At the outer end of the magazine there are provided rear and front yielding tip supports 80 and 81, respectively, each mounted on parallel suspension links 82 and held yieldingly by springs 83 in position to support the tip of the bobbin. The rear support 80 has a downwardly and forwardly extending tip guiding surface 84 which is extended downwardly slightly at the lower end thereof to afford support for the tip of the bobbin. The front support 81 has a somewhat similar surface 85 extending downwardly and rearwardly. The tip supports 80 and 81 may be substantially the same as shown in Patent No. 1,563,592.

Except as to be noted hereinafter the matter thus far described is of common construction, being substantially the same as set forth in the previously mentioned patents all of which are used in the commercial multicolor bobbin changing magazines as built in this country.

As previously stated, failure of the shuttle S to be properly boxed on a beat of the loom intended for transfer will cause the inner tip end of the shuttle to engage the shuttle feeler 31 and raise the same from the position of Fig. 1 to that of Fig. 4, thereby rocking the shaft 30 in such a direction as to depress rod 43 and permit the latch 31 to descend by gravity. This revokes the transfer but leaves the bobbin B in transferring position. In view of the fact that the pattern may call for a change in the active shuttle on the next beat of the loom it is necessary to discharge the untransferred bobbin from the magazine.

In order to accomplish this result I provide an operating connection between the shuttle feeler 31 and the front butt support 60. This connection includes a rod head 90 adjustably mounted on a rod 91 and provided with a substantially horizontal slot 92 into which projects a pin 93 secured to the arm 64 of the butt support 60. The rear end of the rod 91 is pivoted to the shuttle feeler holder as at 94. The relation of the axes 33, 94 and the pin 93 is such that when the shuttle feeler is in the position shown in Fig. 1 the axis 94 will be below a line joining axis 33 with the pin 93 and the support 60 will be in its rearward bobbin holding position, being held there by the heavy spring 66 which transmits its force through the rod 91 and tends to hold the shuttle feeler yieldingly locked by toggle action in down position. Spring 66 also exerts a downward force on rod 34 tending to hold rock shaft 30 in transfer position with the latch 13 elevated. When the shuttle feeler is in its normal elevated position the axis 94 is slightly above a line joining axis 33 and pin 93, the spring 66 under these conditions holding the shuttle feeler yieldingly locked in raised position, and by previously described connections serving also to hold shaft 30 in normal non-transferring position with the latch 13 down.

In operation, the parts will be in the position indicated in Fig. 4 with the shuttle feeler 31 raised and with the front bobbin butt support 60 in forward non-holding position. When a transfer is called as previously described the shuttle feeler and holder 32 will turn in a clockwise direction as viewed in Fig. 1 about axis 33 and move down

to the shuttle feeling position shown in Fig. 1, the force of the spring 66 acting through the rod 91 and assisting gravity in moving the shuttle feeler down to feeling or transfer position.

5 In view of the fact that the center 94 under these conditions is at a distance below a line joining centers 33 and 93 greater than that existing when the parts are in the position shown in Fig. 4, the butt support 60 will be permitted 10 to move rearwardly in bobbin holding position. As a bobbin is released therefore by one or another of the vertical slides the butt thereof will move to the position shown in Fig. 1 and be held there by supports 50 and 60. If thereafter the transfer 15 is normal the bobbin will move down into the shuttle and as the lay moves forwardly the box back 100 will engage the shuttle feeler and lift the same from the position shown in Fig. 1 to that shown in Fig. 4. The shuttle back carries 20 the shuttle feeler almost to its highest position, but as the center 94 raises above a line joining axis 33 and 93, the spring 66 will continue the upward motion of the shuttle feeler, moving the latter somewhat above the box back so that on successive 25 forward beats of the lay there will be no contact between the box back and the shuttle feeler.

If the transfer is revoked, however, the shuttle 30 will raise the shuttle feeler from the position of Fig. 1 to that of Fig. 4, and in doing so will exert a forward thrust on rod 91 which will be transmitted through the head 90 to the axis 93, thereby causing rocking of the shuttle feeler 68 in a left hand direction around its pivot 65 as viewed in Fig. 1. This occurs while the rear 35 bobbin butt support 50 is stationary, hence the butt of the bobbin rolls down along the surface 55, and since the latter is directed forwardly the bobbin will move not only downwardly but also 40 forwardly as indicated in Fig. 4, where the front of the loom is at the right. It is to be understood that even though transfer is revoked by a misplaced shuttle resulting in the elevation 45 of the shuttle feeler, yet the ultimate setting of the magazine is effected by engagement of box back 100 and the shuttle feeler as the lay approaches its extreme forward position.

In order that the tip end of the bobbin may also 50 be directed forwardly as it drops the support 60 has secured thereto a rod 110 which extends in a direction parallel to the bobbin awaiting transfer and lies behind a lug 111 on the bobbin tip support 81. As the support 60 is moved forwardly rod 55 110 will move from the full to the dotted line position shown in Fig. 5, moving the support 81 to the dotted line position away from the tip of the bobbin, permitting the latter to roll down the forwardly extending surface 84 of the rear support 80, the tip of the bobbin therefore moving 60 forwardly as indicated in Fig. 5, where the front of the loom is at the left.

It has been common practice heretofore to release the rear butt support for an untransferred 65 bobbin, the discharged bobbin being required to move down the front supports and be directed rearwardly toward the lay. As set forth hereinbefore it will be understood that the release of the forward bobbin supports permits the discharging 70 bobbin to move along the rear supports and to derive from the latter a direction of motion which is forward relatively to the lay, as indicated clearly in Figs. 4 and 5. The effect of this is to lessen the likelihood of breakage inasmuch as the outgoing bobbin is given a direction of motion 75

generally the same as that of the advancing lay and away from the latter.

From the foregoing it will be seen that I have provided simple means for permitting an untransferred bobbin to be discharged from the magazine 5 in a direction which is generally forward as well as down, thereby moving the outgoing bobbin along a path which is forward with respect to the lay and lessening the likelihood of breakage. It will also be seen that spring 62 acts through the 10 connections already described to control the position of the shuttle feeler, the rock shaft 39 and the latch 13. It should be noted that the structure shown in Fig. 6 omits the compression spring ordinarily employed between arm 37 and lever 15 arm 49. It will also be seen that actuation of the butt support 60 serves to give a forward motion to the front tip support 81 so that both ends of the bobbin are permitted to move forwardly at discharge. 20

Having thus described my invention it will be seen that changes and modifications may be made therein by those skilled in the art without departing from the spirit and scope of the invention and I do not wish to be limited to the 25 details herein disclosed, but what I claim is:

1. In a weft replenishing loom, a lay movable back and forth therein, rear bobbin supports having downwardly and forwardly inclined surfaces to assist in supporting a bobbin in transfer position over the lay when the latter is forward, front yieldable supports for the bobbin in transfer position, and means movable by a force derived from the lay to move the front 30 supports forwardly to release an untransferred 35 bobbin, the latter thereupon rolling downwardly and forwardly along the rear supports along a path extending forwardly with respect to the lay.

2. In a weft replenishing loom, a lay movable back and forth therein, rear bobbin supports having downwardly and forwardly inclined surfaces to assist in supporting a bobbin in transfer position over the lay when the latter is forward, a pair of spaced yieldable supports for 45 the front of the bobbin, an element moving with the lay, and means operated by the element to move said front supports forwardly to release an untransferred bobbin, the latter thereupon rolling down the rear supports in a direction 50 forwardly with respect to the lay.

3. In a weft replenishing loom, a lay movable back and forth therein, rear bobbin supports having downwardly and forwardly inclined surfaces to assist in supporting a bobbin in transfer position over the lay when the latter is forward, a pair of spaced yieldable supports for the front of the bobbin, and means operated by the lay and effective subsequent to the time 55 for the beginning of a normal transfer operation to move the forward supports forwardly, the untransferred bobbin thereupon rolling down the rear supports in a direction forwardly with respect to the lay.

4. In a weft replenishing loom, a lay movable back and forth therein, rear bobbin supports having downwardly and forwardly inclined surfaces to assist in supporting a bobbin in transfer position over the lay when the latter is forward, a yieldable front bobbin butt support, a yieldable front bobbin tip support movable by the butt support, a member having an operating movement subsequent to the normal time for the start of a transfer operation, and means operated by the member to move the front butt sup- 70 75

- port forwardly and also cause forward movement of the front tip support, whereupon the untransferred bobbin rolls down the downwardly and forwardly inclined surfaces of the rear support along a path extending forwardly with respect to the lay.
5. In a weft replenishing loom, a reserve bobbin magazine, a lay movable back and forth under the magazine, means to support a bobbin in transfer position when the magazine is set for transfer and including a downwardly and forwardly inclined surface to engage and position the rear of a bobbin in transfer position, mechanism to reset the magazine subsequent to the normal time for beginning of a transfer operation, and means operated by the mechanism to release an untransferred bobbin and cause the latter under the action of gravity to move down said forwardly and downwardly inclined surface along a path extending forwardly with respect to the lay.
6. In a weft replenishing loom, a lay movable back and forth therein, rear bobbin supports having downwardly and forwardly inclined surfaces to assist in supporting a bobbin in transfer position over the lay when the latter is forward, a shuttle feeler effective to revoke a transfer, front yieldable supports to cooperate with the first named supports to position a bobbin for transfer, the bobbin remaining on said supports after a revoked transfer, and means rendering the shuttle feeler operative to move the front supports forwardly to release the untransferred bobbin, the latter rolling along the downwardly and forwardly inclined surfaces of the rear supports and moving along a path extending forwardly with respect to the lay.
7. In a weft replenishing loom, a magazine for reserve bobbins, a lay movable backwardly and forwardly under the magazine, means to position a bobbin for transfer including downwardly and forwardly extending surfaces in engagement with the rear of a bobbin in transfer position, a member having an operating movement subsequent to the normal time for the start of a transfer operation, and means operated by the member to free the bobbin so that the latter is able to roll under gravity along the downwardly and forwardly extending surfaces in a path extending forwardly with respect to the lay.
50. 8. In a weft replenishing loom, a shuttle feeler, a transfer latch, a yieldable bobbin support to hold a bobbin in transfer position, means con-

necting the support and shuttle feeler, means connecting the shuttle feeler and latch to cause said latch and shuttle feeler to move together, and a single spring tending to move the support to bobbin holding position and operative through both of said means to position the shuttle feeler and latch.

9. In a weft replenishing loom, a shuttle feeler, a transfer latch, a yieldable bobbin support to hold a bobbin in transfer position, means connecting the support and shuttle feeler, means connecting the shuttle feeler and latch to cause said latch and shuttle feeler to move together, and a single spring connected to the support tending to move the latter to bobbin holding position and acting through the first named means to position the shuttle feeler.

10. In a weft replenishing loom, a shuttle feeler element, a transfer latch element, a bobbin support element, means to connect the support element to the feeler element and cause them to move together, other means connecting the feeler element and latch element causing them to move together, and a spring acting on one of the elements and operative through both of said means to position all of the elements.

11. In a weft replenishing loom, a shuttle feeler element movable from normal to shuttle feeling and transfer position, a transfer latch element movable from normal idle to transfer position, a bobbin support element movable from non-supporting to supporting transfer position, means to cause said elements to move together, and a single spring for said elements to cause all the elements to move to transfer position.

12. In a weft replenishing loom, a shuttle feeler element, a bobbin support element, both elements movable from normal to transfer position, a connection between the elements causing them to move together, said connection and one of the elements constituting a toggle lock to hold the elements in normal or transfer position, a transfer latch element movable from normal to transfer position, connections between the feeler and latch elements causing them to move together from normal to transfer position, and a spring for said elements to hold the toggle lock yieldingly in position and act through said connections to move the elements from normal to transfer position.

WALTER H. WAKEFIELD.
